UNITED STATES PATENT OFFICE.

EDWARD F. CALDWELL, OF BROOKLYN, NEW YORK.

DESIGN FOR A CHANDELIER.

SPECIFICATION forming part of Design No. 24,549, dated August 13, 1895.

Application filed June 11, 1895. Serial No. 552,488. Term of patent 3½ years.

To all whom it may concern:

Be it known that I, EDWARD F. CALDWELL, a citizen of the United States, residing in the city of Brooklyn, county of Kings, and State of New York, have invented and produced a new and original Design for Chandeliers; and I do hereby declare that the following is a full, clear, and exact description of the same, reference being had to the accompanying drawing, forming part thereof, which illustrates my design for a light-fixture.

The essential feature of my design consists of a chandelier provided with fluted pear-shaped forms 1, having flattened large and small ends and longitudinal corrugations extending and tapering substantially from the large end to the small end.

In the accompanying illustration of my de-

sign four of these corrugated pear-shaped forms (their corrugations vanishing in rounded extremities) are shown with other ornaments, presenting a highly ornamental appearance. It will be seen, however, that each pear-shaped form 1 forms a complete design in itself for the ornamentation of a light-fixture, and such is the subject of this application.

I claim as my invention—

The design for a chandelier substantially as herein shown and described.

In testimony whereof I have hereunto set my hand this 11th day of March, 1895.

EDWARD F. CALDWELL.

In presence of—

Wm. H. SMITH,

G. M. LEE.
